UNITED STATES PATENT OFFICE.

JAMES O. WATSON AND CONRAD A. SIPE, OF FAIRMONT, WEST VIRGINIA.

WEDGE FOR MINING COAL.

SPECIFICATION forming part of Letters Patent No. 356,564, dated January 25, 1887.

Application filed February 17, 1886. Serial No. 192,220. (No model.)

To all whom it may concern:

Be it known that we, JAMES O. WATSON and CONRAD A. SIPE, of Fairmont, in the county of Marion and State of West Virginia, have 5 invented a new and Improved Coal Wedge and Breaker, of which the following is a full, clear, and exact description.

The object of our invention is to provide a device for breaking down coal, whereby the 10 use of powder or other dangerous explosives heretofore used for that purpose is entirely done away with, thus lessening the danger and greatly improving the condition of the coal delivered from the mine.

15 Our invention consists in the construction and arrangement of parts, as will be herein-after fully described and claimed.

Reference is to be had to the accompanying drawings, forming a part of this specification, 20 in which similar letters of reference indicate corresponding parts in both figures.

Figure 1 is a longitudinal sectional view of our improved coal wedge and breaker. Fig. 2 is an end view of the instrument, the collar 25 and washer being removed and the shaft being in section.

A represents a cylinder made up of sections $a a'$, said sections being semi-cylindrical in cross-section, and each section being formed 30 with a tapering groove, as $b b'$, said grooves being so arranged and proportioned that when the sections $a a'$ are brought together, as best shown in Fig. 2, there will be formed a rectangular recess, c , within which there is fitted 35 and arranged a wedge-shaped block, B. This wedge-shaped block B is formed with a central threaded socket, d , within which there is fitted a threaded end, C, of a shaft, D. In use the end of the cylinder A is inserted within

the hole drilled in the coal until a washer, E, 40 strikes against the face of the coal.

Just beyond the washer E there is arranged a collar, F, which is secured to the shaft D by a set-screw, f, and it will readily be understood that by turning the shaft D the wedge 45 B will be drawn within the recess c , and as it is so drawn in the sections $a a'$ of the cylinder A will be expanded and the coal will be broken down, it being understood that prior to the introduction of the cylinder the coal 50 has been "undercut" and "sheared." The washer E, bearing against the face of the coal, and being in turn borne upon by the collar f, prevents the shaft D from being drawn inward when turned within the threaded socket of the wedge B.

Having thus fully described our invention, what we claim as new, and desire to secure by Letters Patent, is—

As an improved article of manufacture, a wedge for breaking down coal, consisting in the cylinder A, formed of the two semi-cylindrical independent sections $a a'$, each having a tapering groove, $b b'$, to form the central rectangular recess, c , the wedge B within said recess, and having a rectangular shape in cross-section and a longitudinal threaded aperture, the loose washer E on the shaft, and forming a bearing, as set forth, the collar F on the shaft adjacent to the outside of the said washer, and the set-screw for the said collar, substantially as set forth.

JAS. O. WATSON.
CONRAD A. SIPE.
